UNITED STATES PATENT OFFICE.

JOHN SOLARCYK, OF PERTH AMBOY, NEW JERSEY, ASSIGNOR OF ONE-HALF TO
STANISLAW MIDURA, OF PERTH AMBOY, NEW JERSEY.

SHIP STABILIZER.

Application filed April 22, 1922. Serial No. 555,958.

To all whom it may concern:

Be it known that I, JOHN SOLARCYK, a citizen of Poland, residing at Perth Amboy, in the county of Middlesex and State of New Jersey, have invented certain new and useful Improvements in Ship Stabilizers, of which the following is a specification.

This invention relates to certain new and useful improvements in ship stabilizers and has particular reference to the provision of a plurality of floats shiftably connected to a boat, to be placed in operative and inoperative positions.

A further object of the invention has reference to a ship stabilizer embodying a plurality of float devices adjustably connected to a ship upon the opposite sides thereof and normally occupying positions outwardly of the body of the ship, and further being capable of a position entirely spaced above the water line when the ship is resting or traveling in shallow water and in harbors.

The invention further includes the provision of stabilizing float attachments for ships with motive power employed for moving the floats to their operative and inoperative positions.

A still further object of the invention embodies in a stabilizing float of the type above set forth, manually operable means for varying the normal position of the float relative to the ship carrying the same, compensating for draughts or ships of various sizes.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a top plan view of a ship provided with the improved stabilizing floats with the floats in their extended operative positions and showing the power devices for shifting the floats,

Figure 2 shows by dotted lines, a side elevational view of the ship with the stabilizing floats carried by the side thereof retracted to their inoperative position,

Figure 3 is a detail sectional view taken on line III—III of Fig. 1 showing one of the

stabilizing floats extended to its operative 55 position,

Figure 4 is a detail sectional view similar to Fig. 3 showing the float retracted to its inoperative position,

Figure 5 is a detail sectional view taken on line V—V of Fig. 1 showing the stabilizing floats extended and the operating cables attached thereto,

Figure 6 is a detail sectional view taken on line VI—VI of Fig. 1 showing the stabilizing floats in elevated position with respect to the ship carrying the same,

Figure 7 is a fragmentary side elevational view showing one of the stabilizing floats partially disconnected from the ship and elevated to a position above the water line,

Figure 8 is a side elevational view of the float shown in Fig. 7,

Figure 9 is an enlarged fragmentary side elevational view of a portion of the ship 75 with the stabilizing floats removed showing the adjusting screw for varying the normal position of the float and the cable shifted block moving the float from an inoperative to an operative position.

Figure 10 is a detail sectional view taken on line X—X of Fig. 9 showing the height adjusting screw and screw block for the stabilizing float,

Figure 11 is a detail sectional view taken on line XI—XI of Fig. 10 showing the guide connection between the adjusting screw and the screw block,

Figure 12 is a fragmentary top plan view showing the tool employed for operating the 90 adjusting screw and the pawl and ratchet devices for holding the screw in its adjusted position,

Figure 13 is a detail sectional view taken on line XIII—XIII of Fig. 9 showing the 95 sliding block for shifting the stabilizing floats,

Figure 14 is a detail sectional view taken on line XIV—XIV of Fig. 2 showing the guide connection between said shifting block 100 and the ship,

Figure 15 is a detail sectional view taken on line XV—XV of Fig. 1 showing the motor operated drums upon which the cables for shifting the floats are wound,

Figure 16 is a detail sectional view taken on line XVI—XVI of Fig. 1 showing the cable winding positively shifting the floats,

Figure 17 is a fragmentary top plan view of one of the floats removed from the ship.

Figure 18 is a cross sectional view taken on line XVIII—XVIII of Fig. 17, and

5 Figure 19 is fragmentary front elevational view of one of the floats with the arms pivotally connected thereto.

Referring more in detail to the accompanying drawings, there is illustrated a ship 10 provided upon opposite sides thereof with stabilizing floats, the ship being designated by the reference numeral 1 indicating the upper deck portion thereof while the reference numeral 2 designates the side walls of 15 the ship.

The stabilizing floats associated with the ship are preferably arranged in pairs adjustably connected to the opposite sides 20 of the ship, the floats being of identical construction, and further being transversely aligned adjacent the stern and bow of the ship for independent operation. The float per se, is shown in detail in Figs. 17 to 19 and includes a flat base like portion 3 having inner and outer depending edge flanges 25 4 and 5 respectively through which a rod 6 extends, the rod being anchored against displacement adjacent the flange 4 while the opposite end of the rod projecting outwardly of the flange 5 carries an apertured head or lug 7. The float 3 may be constructed of any suitable material such as cork or wood. As shown in Figs. 17 and 19, end 30 extensions 8 are carried by the outer end 35 of the float 3 adjacent the depending flange 4, and said extensions have secured thereto upwardly extending apertured lugs 9.

A part of the connecting means between the float and the side walls 2 of the ship 40 is shown more clearly in Figs. 9, 13 and 14 and includes the provision of a pair of spaced guide bars 10 extending vertically and projecting outwardly of the sides 2 of the ship, the adjacent faces of the guide 45 bars 10 carrying tongues 11 that are positioned in opposite grooves 12 formed in the block 13 that is freely slidable between the guide bars. The sliding block 13 carries an outwardly directed extension 14 having an opening 15 therein to accommodate 50 the journalling of a pulley 16 intermediate the upper and lower ends thereof, the upper end of the block extension 14 being provided with an eye 17, while the lower end 55 carries spaced apertured lugs 18, shown more clearly in Figs. 9 and 13. The apertured lug 7 of the bar or rod 6 carried by the float 3 is positioned between the apertured lugs 18 and pivotally secured there- 60 to by a pin or other securing means shown in Figs. 3 to 6.

The connection between the outer end of the float 3 and the side walls 2 of the ship includes manually shiftable mechanism as 65 shown in Figs. 9 to 12, these devices being

arranged at opposite sides of the sliding block 13, and each embodying a rectangular frame having side walls 19 and top and bottom walls 20 and 21 respectively. The adjacent inner faces of the vertical side 70 walls 19 carrying spaced vertically extending tongues 22 are associated with a grooved screw block 23 vertically shiftable between the side walls 19. A vertically extending screw 24 swiveled at its lower end 75 as at 25 in the bottom wall 21 of said frame, has the upper end thereof projecting through the top wall 20 with a ratchet wheel 26 secured thereto, and further having a wrench engaging end 27 positioned 80 above said ratchet wheel, the screw block 23 having a threaded bore for the reception of the adjusting screw 24, this construction being clearly shown in Fig. 10. An apertured lug 28 projects outwardly of the screw 85 block 23 while a link arm 29 bifurcated at its opposite ends as at 30 is pivotally secured to the apertured lug 28 of the screw block, and also to the adjacent apertured lug 9 carried by the float 3, this connection being 90 clearly shown in Fig. 2.

The two screw blocks 23 arranged at opposite sides of the cooperating sliding block 13 are horizontally aligned and are adapted for vertical adjustment relative to the rectangular frames enclosing the same by said adjusting screws 24, there being illustrated in Fig. 12, a wrench 31 having a toothed end 32 adapted for engagement with the teeth of the wheel 26, 100 while a link 33 carried by the wrench 31 has the free end thereof positioned on the wrench engaging end 27 of the screw so that movement of the wrench 31 in either direction will cause a rotation of the screw 105 24 to effect the raising or lowering movement of the screw block 23. To hold the screw 24 and block 23 in adjusted set position, pivoted pawls 34 carried by the top wall 24 of the rectangular frame are moved 110 into engagement with said toothed wheels to prevent rotation of the adjusting screws. It will be seen that the connection between each float and the side wall of the ship embodies the link arm connections 29 between 115 the said lugs 9 and screw blocks 23, and the lug connection 7—18 between the inner end of the float 3 and the sliding block 13.

The mechanism for shifting the float 3 from its operative horizontal position 120 shown in Fig. 3, to its inoperative retracted and vertical position shown in Fig. 4, includes power devices positioned upon the deck 1 of the ship, the power operating devices being more clearly shown in Figs. 1, 125 15 and 16, illustrated as being positioned between the transversely aligned stabilizing floats, and including motors 35 operatively connected to shafts 36 journaled in spaced standards 37 while cable drums 38 arranged 130

in pairs are fixed to said shaft intermediate the standards. The cable connection between the drums 38 and the sliding blocks 13 are shown more clearly in Figs. 9, 15 and 16, the cable 39 being secured at one end as at 40 to the upper end of the sliding block extension 14 shown in Fig. 13, and passing over a pulley 41 journaled on the gunwale of the ship, the cable being directed beneath and wound upon, and secured to the adjacent drum 38 as shown at the left hand end of Fig. 1. The other cable 42 associated with the sliding block 13 is secured at one end 7 as at 43 to the lower end of one of the side bars, shown in Fig. 9, the cable passing through the block extension 15 and over the pulley 16, being then directed downwardly and beneath the pulley 44 secured to the side of the ship adjacent the opposite side bar 10, and then passes upwardly over the pulley 45 journaled upon the gunwale of the ship in proximity of the pulley 41 for passage over the adjacent drum 38 to be wound and secured thereon as shown in Fig. 1. *

When the stabilizing floats 3 are in their retracted vertical position as shown in Fig. 4, the cable 39 is completely wound upon the drum 38 while the cable 42 is unwound from its supporting drum, the sliding block 13 occupying its uppermost position in the guide bar 10 as shown in Fig. 9, the float 3 being vertically positioned adjacent the side wall 2 of the ship while the link arms 29 connecting the outer ends of the float to the ship are moved inwardly toward the ship. When it is desired to move the floats to their extended operative positions, the motor devices 35 are placed in operation to effect rotation of the drums 38, the cable 39 being unwound from its associated drum 38 while the cable 42 is simultaneously wound upon its drum 38, the winding of the cable 42 effecting a lowering movement of the sliding block 13 as will be clearly obvious upon an inspection of Fig. 9, the sliding block moving to a position adjacent the lower end of the slide bars 10. During this movement, the link arm connection 29 between the floats 3 and the screw blocks 23 are moved outwardly at their lower ends to carry the floats 3 to a substantially horizontal position as shown in Figs. 3 and 5. To compensate for the draught of different ships, the horizontal position of the floats 3 may be changed relative to the ship as indicated in Fig. 6, either to raise or lower the same, this movement being effected by the screw blocks 23, said screw blocks being vertically shifted by the adjusting screws 24 within the rectangular guide frame 19 and being retained in said adjusted positions by the pawls 34 engaging the toothed wheels 26 as shown in Fig. 12. When the ship is travelling in shallow water, such as harbors,

and it being desired to remove the stabilizing floats from the water, the pivot connections between the ends of the link arms 29 and the screw blocks 23 are disengaged, permitting the floats to move upon their pivot lug connections 7-18 to be elevated to the positions shown in Figs. 7 and 8, while a cable 46 shown in Fig. 8 connected to the free ends of the link arms 29 is secured to the deck of the ship to maintain the link arms and floats in their elevated positions.

While there is herein shown and described the preferred embodiment of the present invention, it is nevertheless to be understood that minor changes may be so made therein without departing from the spirit and scope of the invention as claimed.

What is claimed as new is:-

1. In a stabilizing device for ships, a plurality of floats, a plurality of sliding blocks 85 carried by the ship and each pivotally connected to the inner end of a float, link arm connections between the outer ends of the floats and the ship, power devices carried by the ship, pulleys carried by the ship and 90 sliding blocks, and cables extending between the power devices and the ship and blocks and passing over said pulleys for raising and lowering the blocks to shift the floats to their operative and inoperative positions, the connections between the link arms and the ship including vertically adjustable screw blocks 95 for varying the normal positions of the floats.

2. In a stabilizing device for ships, a plurality of floats, vertically sliding blocks carried by the ship and each pivotally connected to the adjacent end of a float, and connections between the outer ends of the floats and the ship, power devices carried by 105 the ship, a cable connection between the power devices and the sliding blocks, and a second cable connected to the ship adjacent the sliding blocks and to said power devices, said cables operating to raise and 110 lower the sliding blocks.

3. In a stabilizing device for ships, a plurality of floats and ship attaching means, each including a float body, vertical side bars carried by the ship, a block vertically slidable between said bars, the float being pivotally connected at its inner end to said block, a vertically adjustable screw block carried by the ship at each side of the sliding block, and link arm connections between the outer 115 end of the float and the screw blocks.

4. In a stabilizing device for ships, a plurality of floats and ship attaching means, each including a float body, vertical side bars carried by the ship, a block vertically slidable between said bars, the float being pivotally connected at its inner end to said block, a guide frame carried by the ship at each side of the sliding block, an adjusting screw within each guide frame, a screw block 125 130

upon said screw within the guide frame, and link arm connections between the outer end of the float and the screw blocks.

5. In a stabilizing device for ships, a plurality of floats and ship attaching means, each including a float body, vertical side bars carried by the ship, a block vertically slid-
able between said bars, the float being pivot-
ally connected at its inner end to said block,
10 a vertically adjustable screw block carried
by the ship at each side of the sliding block,
link arm connections between the outer end
of the float and the screw blocks, and power
devices for vertically shifting the sliding
15 block to shift the float to its operative and
inoperative positions.

6. In a stabilizing device for ships, a plurality of floats and ship attaching means, each including a float body, vertical side bars
20 carried by the ship, a block vertically slid-
able between said bars, the float being pivot-
ally connected at its inner end to said block,
a guide frame carried by the ship at each
side of the sliding block, an adjusting screw
25 within each guide frame, a screw block upon
said screw within the guide frame, link arm
connections between the outer end of the
float and the screw blocks, and power devices
for vertically shifting the sliding block to
30 shift the float to its operative and inoperative
positions.

7. In a stabilizing device for ships, a plurality of floats and ship attaching means, each including a float body, vertical side bars
35 carried by the ship, a block vertically slid-
able between said bars, the float being pivot-
ally connected at its inner end to said block,
link arm connections between the outer end of
the float and said ship, motor operated
40 drums carried by the ship, a cable connec-
tion between one of the drums and the upper
end of the sliding block, and a pulley guided
cable connection between the other drum,
ship, sliding block and guide bar, the opera-
45 tion of the drums effecting movement of the

two cables for raising and lowering the sliding block to shift the float to its operative and inoperative positions.

8. In a stabilizing device for ships, a plurality of floats and ship attaching means, 50 each including a float body, vertical side bars carried by the ship, a block vertically slid-
able between said bars, the float being pivot-
ally connected at its inner end to said block,
a vertically adjustable screw block 55 carried by the ship at each side of the sliding
block, link arm connections between the
outer end of the float and the screw blocks,
motor operated drums carried by the ship, a
cable connection between one of the drums 60 and the upper end of the sliding block, and
a pulley guided cable connection between the
other drum, ship, sliding block and guide
bar, the operation of the drums effecting
movement of the two cables for raising and
lowering the sliding block to shift the float
65 to its operative and inoperative positions.

9. In a stabilizing device for ships, a plurality of floats and ship attaching means, each including a float body, vertical side 70 bars carried by the ship, a block vertically slid-
able between said bars, the float being pivot-
ally connected at its inner end to said block,
a guide frame carried by the ship at each
side of the sliding block, an adjusting 75 screw within each guide frame, a screw block
upon said screw within the guide frame, link
arm connections between the outer end of
the float and the screw blocks, motor oper-
ated drums carried by the ship, a cable connec-
80 tion between one of the drums and the
upper end of the sliding block, and a pulley
guided cable connection between the other
drum, ship, sliding block and guide bar,
the operation of the drums effecting movement
85 of the two cables for raising and lowering
the sliding block to shift the float to its
operative and inoperative positions.

In testimony whereof I affix my signature.
JOHN SOLARCZYK.
